UNITED STATES PATENT OFFICE.

LEWIS LARCHAR, OF CEDAR RAPIDS, IOWA.

RAILROAD-RAIL BRACE.

SPECIFICATION forming part of Letters Patent No. 318,634, dated May 26, 1885,

Application filed February 18, 1885. (No model.)

To all whom it may concern:

Be it known that I, LEWIS LARCHAR, of Cedar Rapids, in the county of Linn and State of Iowa, have invented a new and useful Improvement in Railroad-Rail Braces, of which 5 the following is a full, clear, and exact description.

Reference is to be had to the accompanying drawings, forming a part of this specification, 10 in which similar letters of reference indicate corresponding parts in all the figures.

Figure 1 is a side elevation of one of my improved railroad-rail braces shown in connection with a tie and rail. Fig. 2 is a plan 15 view of the same. Fig. 3 is a perspective view of a brace. Fig. 4 is an end elevation of the same. Fig. 5 is a plan view of a brace-blank before being bent.

The especial object of my invention is to provide braces for securing railroad-rails in place 20 upon ties and holding the said rails from being forced outward or spread by the lateral pressure of the engine and car wheels.

The invention relates to a railroad-rail brace 25 made of a right-angled plate having a recess at its right angle, and bent at right angles to form a base-plate, and a wing having its acute angle bent downward to form a point to be driven into the tie, and perforated to receive 30 the fastening-spikes, whereby the said brace will hold the rail to its seat, and will support the said rail against the outward pressure of the engine and car wheels, as will be herein-after fully described and then claimed.

35 A represents a railroad-rail tie, and B represents a railroad-rail, both of which are made in the ordinary manner. The brace is formed of a plate of iron or steel, made in the shape of a right-angled triangle, having a recess, C, 40 at the right angle. The plate is then bent at right angles at a distance from the angle of the recess C about equal to the thickness of a base-flange of a rail, B, at its edge, thus forming a base-plate, D, and a wing, E. The recess C is so formed that the end of the base- 45 plate D will fit squarely against the edge of the base-flange of the rail, the lower edge of

the projecting part of the wing E will fit upon the upper side of the said base-flange, and the end of the said wing will fit against the web 50 of the rail, as shown in Figs. 1 and 2. The sharp outer end of the brace is bent downward at right angles, forming a point, F, which is driven into the tie A, and serves as a spike for holding the brace in place. The base-plate 55 D has two or more perforations, G, formed through it, through which spikes are driven into the tie A.

In using the brace the base-plate D is laid upon a tie, A, with its shoulder or inner end 60 against the edge of the base-flange of the rail, and the end of the wing E against the web of the rail. The point F is then driven into the tie A, and spikes are driven into the tie 65 A through the perforations G in the said base-plate D. With this construction the brace D E will hold the rail B down to its seat, and at the same time will support the said rail against the outward pressure of the engine and car 70 wheels.

Having thus described my invention, I claim as new and desire to secure by Letters Patent—

1. A railroad-rail brace made, substantially as herein shown and described, of a right-angled plate having a recess, C, at its right angle and bent at right angles to form a base-plate, D, and a wing, E, having its acute angle bent downward to form a point, F, to be driven 75 into the tie and perforated to receive the fastening-spikes, as set forth.

2. The combination, with the tie A and the rail B, of the brace having a recess, C, at its right angles, having its acute angle bent downward to form a point, and perforated to receive the fastening-spikes, substantially as 85 herein shown and described, whereby the rail will be held to its seat and will be supported against the outward pressure of the engine and car wheels, as set forth.

LEWIS LARCHAR.
